(57) **CLAIM**

(**) Term: **14 Years**

The ornamental design for a bracket for attaching a cooler to a motorcycle or motorcycle trailer, as shown and described.

(21) Appl. No.: **29/162,895**

DESCRIPTION

(22) Filed: **Jun. 24, 2002**

FIG. 1 is a top, front right side perspective view of a bracket for attaching a cooler to a motorcycle or motorcycle trailer embodying my design;

(51) LOC (7) Cl. **12-06**

FIG. 2 is a right side elevational view of the bracket as seen in FIG. 1 with the broken lines showing a typical cooler exploded therefrom, the cooler not forming part of the design, the left side being a mirror image thereof;

(52) U.S. Cl. **D12/223**

FIG. 3 is a top plan view of the bracket as seen in FIG. 1;
